UNITED STATES PATENT OFFICE.

JULIUS J. LANGER, OF NEW YORK, N. Y.

LOCK.

1,410,581.

Specification of Letters Patent. Patented Mar. 28, 1922.

Application filed January 21, 1921. Serial No. 438,846.

To all whom it may concern:

Be it known that I, JULIUS J. LANGER, a citizen of the United States, and a resident of New York, county and State of New York, 5 have invented certain new and useful Improvements in Locks, of which the following is a specification.

My present invention relates to locks for swinging doors and the like.

10 The objects of the invention are to provide a simple and substantial lock structure which will be "burglar proof" and which will be made up of but relatively few and sturdy parts not likely to get out of order 15 and fully protected against being tampered with.

These objects I have attained by a novel form of construction, combination and arrangement of parts, one practical embodiment of which is disclosed in the accompanying drawings which are to be considered in conjunction with the following specification. The invention, however, is not limited to the particular construction disclosed, inasmuch as certain modifications may be resorted to without departure from the true spirit of the invention, as will be apparent from the scope of the appended claims.

Figure 1 in the drawings referred to is a 30 front elevation of the lock with portions of the cover removed to show the interior construction.

Figure 1^a is a detail sectional view taken on substantially the plane of line 1^a—1^a of 35 Figure 1.

Figure 2 is a horizontal sectional view of the lock as taken on substantially the plane of line 2—2 of Figure 1.

Figure 3 is a partial side elevation illustrating particularly the knob or handle mechanism for releasing the lock.

Figure 4 is a sectional view on substantially the plane of line 4—4 of Figure 3.

One of the important features of my invention is the bolt mechanism, which is of duplex construction, comprising a pair of cooperating jaws 5, 6 in the nature of levers, pivotally supported alongside each other on studs 7, 8 and having notches 9, 10 in their opposed edges, at the free ends thereof to partially receive and slide over the head portion of a keeper 11. This keeper has a pointed or cam faced edge 12 to effect a spreading or separation of the bolts and 55 shoulders 13 at the rear of the cams or in-

clines behind which the notched portions of the bolts snap to secure the parts in locked position. To insure this interlocking engagement of the bolts with the keeper, I provide spring means which may be a piece of spring 60 wire 14 of substantially U-shape as in Figure 1, having portions twisted beneath the heads of the pivot studs 7, 8 and arms 15 engaged with the inner edges of the levers at points in rear of the pivotal supports so 65 as to spread the rear ends of the levers and hence force together the forward ends of the levers or a spring such as shown at 14^a, Figure 3, may be used. The forward or locking ends of the levers are shown as 70 centered and as limited in their closing movement by having their opposing edges arranged for abutting engagement as indicated at 16 (Figure 1). This engagement of the bolt levers also causes them to operate as 75 closure means making access to the lock all the more difficult.

To release the locking jaws from the keeper, I have shown a rollback 17 having angularly turned ends 18, 19 engaging over 80 the outer edges of the bolt levers. This rollback is shown as pivotally supported at 20 at a point between the rearward ends of the levers and as operated in Figure 1, by a lug 21 projecting from the inner end of 85 the key plug of the rim lock 22. To spread the two jaws or bolts equally, I have shown the lower lug 19 on the rollback as of lesser extent than the lug 18 at the opposite end of the rollback so as to compensate for the 90 variations in leverage as these lugs slide over the edges of the levers in the rotation of the rollback (see dotted lines in Figure 1).

At the inside of the door the lock may 95 be controlled by similar rim lock mechanism such as indicated at 23 connected at its inner end with a rollback 24 similar to the first rollback and having lugs at its ends such as indicated at 25, 26 to engage the edges of 100 the bolt levers. In place of this key operated lock mechanism or in addition thereto, I may provide a handle or knob mechanism, for which reason I have indicated in the form shown in Figure 3, a knob at 27 connected directly with the rollback 24, a second knob 27^a being here provided for the outer rollback 17.

In order that the bolts or locking jaws may when desired be secured in their re- 110

tracted and inoperative position, I have shown "hold open" mechanism (Figure 1) in the form of a rotary element 29 carried by a stud or turn-button 30 and provided with 5 cams or inclined shoulders 31 to engage over the studs or pins 32 on the levers. At the inner ends of these cam shoulders, that is, the ends nearest the center of pivotal support, I have indicated depressions or pockets 10 33 to catch and hold the pins 32 and hence to releasably secure the parts in the bolt retracted relation.

The parts described are preferably supported and housed by a casing such as I 15 have indicated at 34, said casing having an end extension part 35 wholly or substantially entirely enclosing the projecting or locking ends of the pivoted bolts and provided with a slot 36 in the side thereof to 20 receive the keeper 12. This housing of the projecting ends of the bolts prevents tampering with the same when the door is open and prevents the insertion of tools for spreading or releasing the bolts. The 25 keeper is shown supported and carried by an angular base member 37 seated in a mortise in the edge of the door casing and the lock casing similarly is secured in a mortise cut in the edge of the door. The extension 35 30 is shown as widened or brought out to the surface at the inside of the door so as to stand flush with the surface of the door-jamb when the door is closed.

In the second form of the invention I have 35 shown how the outer door knob may be "dogged" by means of a slide 36 positioned to engage in a notch 37 provided in the outer rollback and actuated by a lever 38 connected at 39 with the push buttons 40, 41. Also 40 in this form of the invention I have shown at 42 a cylinder lock having a rollback 43 at its inner end arranged to engage an extension 44 at the lower end of the inner rollback 24 which enables the lock to be operated 45 by a key in the hands of an authorized party.

What I claim is:

1. The combination with a door provided with a mortise, of a lock casing set in said 50 mortise, cooperating pivoted bolts mounted in said mortised casing and projecting beyond the edge of the door, a door-jamb provided with a mortise, a shouldered keeper seated in said mortise and arranged to be 55 engaged by the projecting portions of the pivoted locking bolts and a housing for the projecting portions of the locking bolts arranged to close the mortise in the door-jamb.

2. A mortise lock comprising in combination with cooperating door and door frame having mortises at their adjoining edges, a shouldered keeper seated in the mortise in the door frame, a lock casing seated in the mortise in the door and provided with an 60 extension to pass into the mortise in the door frame and cooperating bolts pivoted in the lock casing and projecting into the extension of said casing for engagement with the shouldered keeper.

3. A mortise lock comprising in combination with cooperating door and door frame having mortises at their adjoining edges, a shouldered keeper seated in the mortise in the door frame, a lock casing seated in the mortise in the door and provided with an 65 extension to pass into the mortise in the door frame and cooperating bolts pivoted in the lock casing and projecting into the extension of said casing for engagement with the shouldered keeper, the extension of 70 the lock casing being closed about the projecting portions of the locking bolts except for an opening in only one side thereof to receive the keeper.

4. A mortise lock comprising in combination with cooperating door and door frame having mortises at their adjoining edges, a shouldered keeper seated in the mortise in the door frame, a lock casing seated in the mortise in the door and provided with an 75 extension to pass into the mortise in the door frame and cooperating bolts pivoted in the lock casing and projecting into the extension of said casing for engagement with the shouldered keeper, the extension of 80 the lock casing being closed about the projecting portions of the locking bolts except for an opening in only one side thereof to receive the keeper.

4. A mortise lock comprising in combination with cooperating door and door frame having mortises at their adjoining edges, a shouldered keeper seated in the mortise in the door frame, a lock casing seated in the mortise in the door and provided with an 85 extension to pass into the mortise in the door frame and cooperating bolts pivoted in the lock casing and projecting into the extension of said casing for engagement with the shouldered keeper, the extension of 90 the lock casing being closed about the projecting portions of the locking bolts except for an opening in only one side thereof to receive the keeper.

5. In a lock of the character described, cooperating pivotally operating bolt levers, 100 a shouldered keeper adapted to enter between said bolt levers, rollbacks at opposite sides of the lock pivoted intermediate the bolt levers and having laterally extending actuating lugs at opposite ends of the same 105 positioned to engage over the outer edges of the bolt levers, said rollbacks being independently operable to actuate the bolt levers and dogging means for securing the parts in desired relation.

6. In a lock of the character described, cooperating pivotally operating bolt levers, spring means for rocking the bolt levers in one direction and an operating rollback pivoted intermediate the bolt levers and having laterally extending actuating lugs at opposite ends of the same positioned to engage over the outer edges of the respective bolt levers at different points.

7. In a lock of the character described, cooperating pivotally operating bolt levers, a shouldered keeper adapted to enter between said bolt levers, rollbacks at opposite sides of the lock independently operable to actively engage the bolt levers and means for 115 dogging one of said rollbacks.

8. In a lock of the character described, cooperating pivotally operating bolt levers, a shouldered keeper adapted to enter between said bolt levers, rollbacks at opposite 120 sides of the lock independently operable to actively engage the bolt levers and means for 125 dogging one of said rollbacks.

sides of the lock independently operable to actively engage the bolt levers, means for dogging one of said rollbacks and key actuated means for operating the other rollback.

- 5 9. In a lock of the character described, cooperating pivotally operating bolt levers, a shouldered keeper adapted to enter between said bolt levers, rollbacks at opposite 10 sides of the lock independently operable to actively engage the bolt levers and means for dogging one of said rollbacks, knobs at opposite sides of the lock for turning the rollbacks, cylinder lock mechanism provided 15 with a rollback, the undogged rollback afore-

said having an extension standing in the path of said cylinder lock rollback.

10. In a lock of the character described, cooperating pivotally operating bolt levers, a shouldered keeper adapted to enter between 20 said bolt levers, a rollback having parts engaging the bolt levers for operating the same and provided with an extension and cylinder lock mechanism having a rollback engageable with said extension of the bolt 25 lever operating rollback.

In witness whereof, I have hereunto set my hand this 15th day of January 1921.

JULIUS J. LANGER.
